No. 824,705.

PATENTED JULY 3, 1906.

J. B. BELL.
LINOTYPE MACHINE.
APPLICATION FILED DEC. 12, 1905.

UNITED STATES PATENT OFFICE.

JEROME B. BELL, OF WILMINGTON, DELAWARE.

LINOTYPE-MACHINE.

No. 824,705.

Specification of Letters Patent.

Patented July 3, 1906.

Application filed December 12, 1905. Serial No. 291,476.

To all whom it may concern:

Be it known that I, JEROME B. BELL, a citizen of the United States, and a resident of Wilmington, county of Newcastle, State of Delaware, have invented certain new and useful Improvements in Linotype-Machines, of which the following is a specification.

The present invention relates to means for automatically stopping a typographic machine when the galley is full or when the matter in the galley has reached a predetermined amount.

In the accompanying drawings I have illustrated the invention in connection with a Mergenthaler linotype-machine, to which it is especially adapted, although it may be applied to other composing-machines.

Figure 1 of the drawings shows in front elevation a portion of a linotype-machine to which my invention is applied, and Fig. 2 is a side elevation of a portion of Fig. 1.

In the linotype-machine as illustrated, for instance, in United States Patent No. 436,532 to Ottmar Mergenthaler there is provided means for automatically stopping the machine in the event of anything occurring to prevent the proper presentation of the matrices to close the mold. This mechanism, which is fully described in lines 3 to 54, page 11, of the patent, operates to disconnect the driving-clutch when the yoke which carries the matrices fails to descend so as to bring the matrices into register with the mold-opening.

Referring to the accompanying drawings, N indicates a vertically-movable yoke which carries the matrices to the casting position, and a^{23} indicates a vertically-movable rod which normally is raised into the path of the yoke by a spring a^{24} . When the yoke carries the matrices into proper position for casting, it contacts with the upper end of the rod a^{23} and moves the said rod downward, in which case the casting takes place as usual. If the yoke for any reason is prevented from reaching its casting position, the rod a^{23} will not be carried down, and in consequence the driving-clutch will be thrown open and the machine stopped. It is thought unnecessary to

illustrate and describe the stopping mechanism in the present case, as it is fully illustrated and described in the patent to Mergenthaler above mentioned.

It sometimes happens that the operator will fail to notice when the galley is full of slugs, with the result that a number of slugs

are dumped upon the floor and more or less injured, involving delay in picking them up, sorting, and rearranging them and sometimes in recasting them. To avoid this difficulty, I provide means for automatically stopping the machine when the galley is full, and instead of providing special connections to the driving-clutch I avail myself of the connections which are operated by the yoke N and the rod a^{23} , which are shown in the Mergenthaler patent.

The galley 1 is provided with a preceder or movable holder 2, of suitable construction, against which the slugs or type-bars 3 rest. The preceder slides in the galley in advance of the line of slugs, the latter being pushed to the left one by one as they are ejected from the mold into the galley through the vertical slot 4.

Above the galley at its left end is a lever 5, which for convenience may be pivoted on the shank of the clamp 6. The lever 5 is provided with an arm 7, extending into the path of the preceder 2. I prefer to pivot the arm 7 to the lever, in order that it may be moved to one side, as indicated in dotted lines, to facilitate taking the slugs out of the galley or for arresting the action of the automatic stop, if so desired. As shown, the arm 7 is pivoted to the lever at 8, and its upper end has an inturned point 9, which springs into an opening in the lever to hold the arm yieldingly in line with the lever. Connected to the upper end of the lever 5 is a bar 10, the right end of which is adapted to move under the yoke N and prevent it from moving down to its lowermost position when the lower end of the lever 5 is rocked to the left. As shown in Fig. 1 of the drawings, the galley is filled with slugs to the desired limit, and it will be evident that the addition of one or two slugs will cause the preceder 2 to move to the left sufficiently to throw the bar 10 under the yoke N. On attempting to cast another line the yoke N will be prevented from bringing the matrices properly to the mold, the rod a^{23} will remain in its upper position, and the machine will therefore be thrown out of operation.

It will be evident that my present invention may be embodied in many different forms and that it is not necessarily limited to the linotype-machine in connection with which it is illustrated, but may be applied to typographic machines generally. The specific mechanism illustrated, however, is very

simple, and it can be applied to a commercial linotype-machine at trifling cost without changing any parts at present in the machine.

Having described my invention, what I claim, and desire to secure by Letters Patent, is—

1. In a typographic machine, the combination with a galley, of an automatic stop mechanism adapted to be operated by the accumulated matter in the galley.

2. In a typographic machine, the combination with a galley, of a preceder against which the product of the machine is assembled, and means adapted to be operated by said preceder for automatically stopping the machine when a predetermined amount of matter has been assembled in the galley.

3. In a linotype-machine, the combination with the yoke N and with means for automatically stopping the machine when the yoke fails to reach its casting position, of a galley, and means for obstructing the movement of said yoke to casting position, said means being adapted to be operated by the accumulation of type-bars in the galley.

4. In a linotype-machine, the combination with the yoke N and with means for automatically stopping the machine when the yoke fails to reach its casting position, of an obstructing-piece 10 movable into and out of the path of the yoke, a part movable by the accumulated matter in the galley, and a connection between said piece and said part, for the purpose set forth.

35 5. In a linotype-machine, the combination

with the yoke N and with means for automatically stopping the machine when the yoke fails to reach its casting position, of a lever having an arm adapted to be operated by the movement of the accumulated matter 40 in the galley, and a part 10 connected with said lever and movable into and out of the path of the yoke.

6. In a linotype-machine, the combination with the yoke N and with means for automatically stopping the machine when the yoke fails to reach its casting position, of an obstructing-piece adapted to be moved into and out of the path of the yoke, a lever connected with said obstructing-piece and a part 50 45 movable connected with said lever and adapted to be thrown into and out of position to be operated by the accumulated matter in the galley.

7. In a linotype-machine, the combination 55 with the yoke N and with means for automatically stopping the machine when the yoke fails to reach its casting position, of the clamping-shank 6, the lever pivoted thereon, and means connected with said lever for intercepting the yoke, said lever being adapted to be operated by the accumulated matter in the galley.

In testimony whereof I affix my signature in presence of two witnesses.

JEROME B. BELL.
